United States Patent Office

Des. 205,001
Patented June 7, 1966

205,001

FLUIDS FILTER

Julius L. Englesberg, 123 Knollwood Road,
Rockville Centre, N.Y.

Filed Apr. 23, 1965, Ser. No. 84,943

Term of patent 14 years

(Cl. D46—1)

FIG. 1 is an elevation view of a fluids filter, showing my new design;

FIG. 2 is a top plan view thereof; and

FIG. 3 is a bottom plan view thereof.

What I claim is:

The ornamental design for a fluids filter, substantially as shown.
